UNITED STATES PATENT OFFICE.

JOHN JOSEPH O'BRIEN, OF COALINGA, CALIFORNIA.

DESIGN FOR A LIQUID DROPPER AND POURER.

43,474.

Specification for Design.

Patented Jan. 21, 1913.

Application filed November 14, 1912. Serial No. 731,428. Term of patent 14 years.

To all whom it may concern:

Be it known that I, JOHN J. O'BRIEN, a citizen of the United States, residing at Coalinga, in the county of Fresno and State of California, have invented a new, original, and ornamental Design for a Liquid Dropper and Pourer, of which the following is a specification, reference being had to the accompanying drawing forming part thereof.

Figure 1 is a perspective view of a liquid

dropper and pourer, showing my new design; Fig. 2 is an edge view of the same.

I claim:

The ornamental design for a liquid dropper and pourer, as shown.

JOHN JOSEPH O'BRIEN.
